UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF PROVIDENCE, RHODE ISLAND, A CORPORATION OF DELAWARE.

HANGER FOR WALL RADIATORS AND THE LIKE.

Application filed October 2, 1923. Serial No. 666,057.

This invention relates to improvements in hangers for wall radiators and the like. It is directed particularly to means for holding such a radiator upright by a single hanger on the wall, notwithstanding that it is not evenly balanced with respect to the hanger.

Many times it would be most convenient to support a small radiator on a single hanger, but difficulties arise because a specific location is desired for the radiator, and the median line of the desired radiator location often does not coincide with that vertical plane wherein a sufficiently strong support on the wall can be had. This is particularly so where the wall support is a stud, bolt or screw, set and embedded during the making of a rough concrete or brick wall, before the exact location of the radiator can be known. Moreover as such radiators rest rather loosely on secondary studs, or brackets, which project between its pipes, there is a tendency of the radiator to rotate about each such support. It has accordingly been customary to provide two wall screws and two hangers sufficiently spaced apart for one to be near each end of the radiator. It has been known that a single screw and hanger would be strong enough, but a single one could not be made to serve in other necessary respects, as indicated above.

It is an object of the present invention to provide a wall hanger of such type that a single unit can serve. This may hang vertically from a single stud, and hold the radiator also vertical, and in stable equilibrium, even though the center of gravity be at a little distance from the vertical plane through the stud, minor lateral stresses being carried by the piping connections. A feature of the invention is the provision of a simple wall plate maintainable in position on the wall with only the single stud, without the auxiliary support of additional lugs set into the wall as has been heretofore required in apparatus proposed for radiator hangers. Another feature is the provision of a tie rod depending vertically from the said plate and having associated with its lower end two spread foot brackets, separately adjustable laterally on the single hanger. However much the vertical plane

of the single wall stud may be off from the center of gravity of the radiator (within ordinary working limits) these two brackets 55 can be set so that the line of gravity will fall between them; and thus the weight of the radiator will rest upon them firmly and in stable equilibrium, so far as the hanger is concerned. The hanger and the radiator 60 thus become practically a unit. If the center of gravity of the combination is out of the vertical plane of the wall stud a tendency to swing together down around it results, but the horizontal component of this is of 65 very minor consequence (especially if the wall support be well above the center of gravity) and is easily sustained by the lateral piping connections, which can also be utilized to adjust the angle of the radiator 70 if necessary. The upper horizontal tie to the hanger carries no weight for the support provided by the foot brackets is ample. If it works loose, as may happen, the radiator 75 columns retain their verticality because resting with the center of gravity falling between two supporting points.

Another feature resides in the hook manner in which the foot members are mounted, which provides for their instant removal and 80 replacement in a new position, or for the mere slipping of the foot members from one position to another. The said horizontal tie, adjustable transversely of the plate, on an arc about the same stud, engages the upper 85 portion of the radiator to hold it in vertical alignment.

The weight of the radiator will ordinarily be distributed unequally between the foot brackets, and along the foot bar, but this is 90 immaterial as the whole radiator load, except the small horizontal component, is imposed on the bottom of the tie, vertically under the wall stud, or at least in its vertical plane. This stability of support makes 95 a single hanger suffice for fairly heavy and long radiators. Moreover it becomes immaterial whether the radiator is made in even or odd numbers of sections, or is set a little to one side of the stud, for in either case the 100 supports may be so placed that the load is in stable equilibrium on the single tie.

It is intended that the patent shall cover, by suitable expression in the appended

claims, whatever features of patentable novelty exist in the invention disclosed.

In the accompanying drawings:

Figure 1 is a front elevation of a bracket embodying the present invention, with a portion of the supported radiator indicated by dot and dash lines;

Figure 2 is a side elevation of the same;

Figure 3 is a plan, as on line 3—3 of Figure 1, showing the foot bar, with two foot supports thereon (the radiator being omitted);

Figures 4 and 5 are sections on lines 4—4 and 5—5 respectively, of Figure 1, showing details of the upper portion of the bracket;

Figure 6 is a side elevation of a modification, and also shows the bracket as applied to a plain wall having no base board; and

Figure 7 is an elevation of the lower portion of the hanger of Figure 6 (the radiator being omitted) looking toward the wall.

Referring to the drawings, the hanger has a wall plate 10 secured to the wall 12 by a stud 14 set rigidly in the wall, having a screw threaded end projecting, which screw also serves to clamp to the plate a link, 16, at whose free end is mounted the horizontal tie bolt 18, and the spacing washer 20. The latter is wide enough to span the space between adjacent sections *a*, *a*, of the radiator and to overlie their back edges. The outer end or head of the horizontal tie bolt is provided with a smaller washer 22 having a tapering surface fitting inconspicuously between and against the adjacent surfaces of two neighboring sections, so that upon the tie bolt 18 being set up the sections will be drawn tightly against the large washer 20. A vertical tie or hanger of any suitable sort, here represented (Figures 1—5) as a long bolt, 24, depends from a claw formed by outstanding arms 25 on the lower part of the wall plate 10. The upper sides of these arms are recessed to receive and retain its nut 27, so that the bolt may be raised or lowered for vertical adjustments. The under side of said arms 25 may have positioning lugs 25' which keep the bolt 24 from swinging transversely with respect to the wall plate.

A horizontal flat bar 26, set edge up having a central vertical sleeve portion 26' enclosing the lower part of the vertical bolt and resting upon the bolt head 24' at the bottom, is composed of two arms 26^a which extend along the wall in opposite directions from the sleeve. On each arm is mounted a radiator-supporting bracket or foot 28 having a hook 30 at its rear upper end adapted to overlie and engage the top edge of the arm non-rotatably, and being of sufficient width and nicely of fit to maintain the forward projecting portion 32 of the bracket at right angles to the arm. These foot brackets fit between adjacent sections of the radiator,

being somewhat curved on their upper sides to receive the rounded projections *b* that connect the sections.

In case it is desired to set the radiator or to shift it horizontally a distance less than that between sections, the bolt 14 is loosened, and the link 16 is swung to one side or the other from its illustrated vertical position, until the tie bolt 18 is opposite the new location of the space between sections through which it is to extend. At the bottom it is only necessary to slip the foot supports 28 along their respective arms 26^a an amount equal to the shift of the radiator, retaining them engaging their respective projections *b*. Thus the horizontal adjustment of the radiator is made easily possible, for the link is long enough to accommodate the shifting of the sections from their illustrated positions slightly more than half the distance between their spaces; and the adjustability of the foot supports are limited only by the extent of their arms.

An important advantage derived is the support of the radiator in the plane of the wall screw, and the elimination of tendency of the radiator to tip or pitch sidewise along the wall except the trifle which is easily sustained by the piping connection 40. The resting of the radiator on two spread supports to a large degree balances the radiator on the bolt; and the close fit of the sleeve 26' on the bolt 24, prevents the unbalanced portion from tipping the radiator with respect to the vertical bolt 24.

In Figure 2, the form of bracket illustrated is particularly adapted for use when there is a baseboard 34 at the base of the wall in which case a spacing member 36 may be employed to keep the foot support bar 26 away from the baseboard. When the wall has a plain face clear to the floor, a rearward extending ridge 36' may be provided on the bar 26, and this may rest against the wall to keep the arms far enough away from it to allow room for the movements of the foot supports.

Figures 6 and 7 disclose a somewhat simpler though equally efficient hanger in which the vertical tie bolt is a piece of tubing pipe, 38, a portion 38' of which at its upper end is flattened and offset to rest directly against the wall 12. This portion is pierced by the stud 14, which clamps it, and with it the link 16', rigidly in place. The lower end of the pipe 38 is threaded to receive an adjusting nut 40 which serves as a rest for a piece of channel bar 42 which extends parallel with the face of the wall. This bar has aligned openings in its parallel sides 42^a through which the pipe 38 passes and at the outer edge of its upper parallel side is provided with an upstanding flange 42^b upon which the radiator-supporting bracket or foot 28' is hooked as heretofore

described. As a precautionary provision against closing of the bracket-supporting channel iron 42, under weight of the radiator, a section of channel iron 44 is slipped 5 into the first channel, with its legs 44^a up-standing to constitute vertical struts. The main channel iron may be so proportioned that its web 42^c will rest against the wall, as seen in Figure 6, or against a base board if 10 such is encountered. With this modification, the vertical adjustment of the foot supports 28' is effected by turning the adjusting nut 40 on the pipe threads, and their horizontal adjustment is made simply by sliding them 15 along the upstanding flange 42^b of the channel iron 42.

Although the invention is illustrated as it may be applied to radiators, it is obvious 20 that its scope is not limited to that, but 20 that it may be applied for holding other objects in positions which are not symmetrical with respect to their support on a wall.

Moreover, although the preferred form of the invention is illustrated, in which the 25 foot brackets 28 slip on the foot bar, 26 or 42, in making the horizontal adjustment of position to a greater or less distance from the vertical tie, it is not essential that the slip should occur at this point for the brackets might be rigid on the foot bar, and the latter movable with them to either side of central position. And although the invention is shown and particularly described in 30 connection with a radiator whose sections 35 make a serrated bottom, it is equally applicable with a radiator having a smooth bottom, in which case the advantages of the spread two-point bottom support for the radiator can be had without making the foot 40 supports adjustable, for the radiator alone might then be set thereon with its center at desired distance to one side of the vertical tie.

I claim as my invention:

45 1. A hanger adapted to be secured to a wall, comprising a vertical tie; a foot-member supported thereby having arms spreading therefrom horizontally; and load-carrying brackets mounted on said arms on both 50 sides of a vertical plane through the tie, said brackets extending in direction from the wall, and being engaged with said arms with rigidity against downward movement and 55 engaging under the bottom of the load, and adapted to be set at variable distances to each side of said tie.

2. A hanger for a wall radiator, comprising a horizontal tie extending outward from the wall for engaging the upper portion of 60 the radiator; a vertical tie extending downward therefrom along the wall and having on each side, at its foot, horizontal extensions 65 parallel to the wall; and a bracket on each said extension, projecting outward from the wall for engaging the lower portion of the

radiator; both the horizontal tie and the brackets being movable toward and from the vertical tie.

3. A hanger for a wall radiator comprising 70 a vertical tie; a bar mounted on the lower end of said tie, having an arm extending horizontally along the wall; and brackets on both sides of said tie, each having a hook 75 engaging said arm non-rotatably, rigidly extending outward therefrom away from the wall, and adapted to receive the bottom of the radiator and support the radiator in an upright position; and means to hold the top of the radiator toward the wall.

4. A hanger for a wall radiator comprising 80 a vertical tie attachable at its upper end to the wall; a channel bar mounted on the lower end of said tie with its web toward the wall and with its open side outward; a flange 85 on the outer edge of the upper side of the channel; and brackets arranged on opposite sides of said tie, each engaging said flange and extending outward away from the wall and adapted to support the radiator in an upright position. 90

5. A hanger for a wall radiator comprising 95 a vertical tie attachable at its upper end to the wall and carrying at its lower end a channel bar whose web is toward the wall and parallel with it, and whose sides extend horizontally outward from the wall; a second channel bar nested within the first, with its web resting on one of the sides of the first and with its sides constituting struts between the sides of the first; and brackets 100 mounted on the first channel bar and projecting outward therefrom to receive the bottom of the radiator at points on opposite sides of the vertical tie. 105

6. A hanger for a wall radiator, comprising 110 a wall engaging stud; a horizontal radiator top-supporting member; and a vertical member having a plurality of arms extending underneath the radiator to engage its bottom; said members being mounted on 115 said stud, separately adjustable with respect thereto, and together adapted to engage the radiator at three separate points two of which are under it and on opposite sides of a vertical plane passing through the center of 120 gravity of the radiator. 125

7. A hanger for a wall radiator, having a wall engaging stud; an arm extending from said stud, provided with means extending underneath the radiator for engaging its bottom at separated points in horizontal direction along the wall below said stud; and another arm extending from said stud adapted to engage the front of the radiator in the region of said stud; said arms being 125 separately adjustable with respect to said stud.

Signed at Boston, Massachusetts, this 18th day of May, 1923.

ALBERT J. LOEPSINGER.
